(57) CLAIM

The ornamental design for a nesting spoon, as shown and described.

DESCRIPTION

FIG. 1 is a front perspective view of a nesting spoon showing my new design.

FIG. 2 is a top plan view thereof.

FIG. 3 is an end view thereof.

FIG. 4 is a front elevation view thereof;

FIG. 5 is a rear elevation view thereof.

FIG. 6 is an opposing end view thereof; and,

FIG. 7 is a bottom plan view thereof.

The broken lines in the figures are for illustrative purposes only and form no part of the claimed design.
